ATTORNEY.

UNITED STATES PATENT OFFICE.

CHARLES S. AITKEN, OF PLANKINTON, SOUTH DAKOTA.

WINDMILL ATTACHMENT.

SPECIFICATION forming part of Letters Patent No. 734,494, dated July 28, 1903.

Application filed August 5, 1901. Serial No. 70,886. (No model.)

To all whom it may concern:

Be it known that I, CHARLES S. AITKEN, residing at Plankinton, in the county of Aurora and State of South Dakota, have invented 5 certain useful Improvements in Windmill Attachments; and I do hereby declare that the following is a full, clear, and exact description of the invention, such as will enable others skilled in the art to which it appertains to make and use the same, reference being had to the accompanying drawings, which form a part of this specification.

This invention relates to a new and novel improvement in windmill attachments.

15 The aim of my invention is to provide an attachment to windmills by means of which the vertical reciprocating movement of the pump-rod may be converted into a power readily applicable to machinery driven by 20 belt or chain communication, as will be described more fully hereinafter.

25 In the accompanying drawings I have shown in Figure 1 a broken section of an ordinary windmill-tower provided with my windmill attachment. Fig. 2 shows a top view, with portions removed, of my attachment. Fig. 3 shows a detail of one of the pawls, while Fig. 4 shows a detail of the guide-plate used in my invention.

30 In the accompanying drawings, 2 and 3 show the uprights of an ordinary windmill-tower, while 4 represents one of the cross-braces. Secured to one or more of the cross-braces 4 of an ordinary windmill-tower is a 35 base-frame comprising the end bars 5 and 5' and the side bars 6 and 6' to form a rectangular frame. Extending upward from this base-frame are the posts 7 7' and 8 8'. The end posts 7 and 8 are connected by means of 40 the frame-bar 30, while the posts or uprights 7' 8' are connected by the frame member 30', the members 40 and 40' being interposed between the frame members 30 30', as is more clearly shown in Fig. 2. Secured to the base-frame member 6' is an upright or standard 45 13, which extends upward a suitable distance and gives support to the shaft H, which shaft upon the opposite side is supported by means of the hanger L, secured, by means of the pin Z', to the upperside frame member 30. This 50 shaft H is provided with a fly-wheel G upon one end and with the belt or chain pulley I

upon the opposite end. Near the fly-wheel G this shaft is further provided with a gear-wheel 28, which meshes with a gear-wheel F, 55 secured to the drive-shaft D. This drive-shaft D is secured to and works within the upper end of the hanger L, as is shown in Fig. 1, and upon the opposite end works within the bearing L', secured to the transverse frame member 30', as is shown in Fig. 2. To this shaft D is secured the large driving-gear F. Approximately intermediate of its length this shaft, which is prevented from working out laterally by means of the collars 65 f and f', is provided with the collars 26 and 27, from the first of which extends the arm B and from the second of which extends the arm B', and interposed between these arms B and B' is the ratchet-wheel E, as shown. 70

In Fig. 3 is shown a detail of the arm B', which is similar to the one marked B. At one end each of the arms B and B' is provided with the pin e and a dog, the first arm B being provided with the dog C and the 75 arm B' with the dog or pawl C', as is shown in Fig. 3. It will be noticed that the pawl C engages the ratchet E from below, referring to Fig. 1, while the pawl or dog C' engages the ratchet E from above. A spring 80 23 is hooked about each arm B and B' in such a manner that the upper end works down upon the pawl, so as to force these pawls C and C' into engagement with the ratchet E. These arms B B' are rocked upward and downward by means of the arms A 85 A', secured to the arms by means of pins 21, one arm being shown in detail in Fig. 3. These arms A A' are in the form of hangers and below by means of a bolt b, secured by 90 means of a nut c, are secured to a rocker-arm 14, which arm 14 works upon a pin a, held within the bearing 12, as is clearly shown. This rocker-arm 14 is provided with a number of openings x. At its free end this rocker-arm is provided with a pin 15, to which is secured a link 16, which link 16 is held by means of a pin 17, which pin 17 forms a part of the clamping-collar 18, secured by means of the screws 19, so that this clamping-collar 95 100 may be adjustably secured to the reciprocating pump-rod 20, as shown.

Positioned adjacent the standards 8 8' is a guide-plate 9, provided with the incision 24

and the slots 25 25'. Secured to the frame member 5' are suitable bolts which pass through the slots 25, and these bolts are secured by means of the nuts 32, so that this 5 guide-plate 9 may be raised and lowered. The rocker-arm 14 works within the slot 24 of the plate 9, and by reason of said slot said arm is prevented moving laterally upon its fulcrum *a*, and accurate vertical movement 10 of the arms A and A' is thus insured. Moreover, by adjustably mounting the plate 9, through the medium of the slots 25 and bolts 32, upon the frame member 5' said plate 9 may be readily raised or lowered to accord 15 with the change of pitch of the arm 14 when its fulcrum-point is changed through the medium of the pin *a* and the openings *x* of the arm 14. Working over the pulley I is a chain or belt which below is carried over the driv- 20 ing-wheel of a mill, feed-cutter, grindstone, or any other machine that is intended to be operated.

As the windmill-wheel operates the pump-plunger 20, the plunger in going downward 25 depresses the lever 14 to raise the arm A', so that the pawl C' engages the ratchet E to rotate the shaft D. At the end of the stroke the hangers descend and the hanger A operates the pawl C to turn the ratchet F, so that 30 as the hangers rise and fall they operate the pawls to engage and revolve the ratchet E, and this rotary movement is imparted to the large gear-wheel F, by means of which it is transferred to the power-shaft H, which is 35 given a steady movement by virtue of the heavy fly-wheel G, secured to the shaft H, and from which shaft the power is transferred, by means of a belt connection, to a suitable machine.

40 The device is simple of construction and can be attached to any machine which is provided with a bar.

Having thus described my said invention, what I claim as new, and desire to secure by 45 United States Letters Patent, is—

1. In an attachment of the class described,

the combination with a supporting-frame, a power-shaft journaled thereon, a driving-shaft also journaled upon said frame and geared to said power-shaft for driving the latter, and ratchet mechanism for actuating said driving-shaft, of a rocker-arm carried by said frame and having an adjustable fulcrum thereon, said rocker-arm having suitable connections for attachment to a reciprocating element to receive motion therefrom, and a guide-plate carried by said supporting-frame and having a slot in which said rocker-arm reciprocates, whereby said rocker-arm is prevented moving laterally upon its fulcrum, said guide-plate being vertically adjustable upon said frame, whereby said plate may be raised or lowered to accord with the change of pitch of the rocker-arm when the fulcrum-point of the latter is changed. 65

2. In an attachment of the class described, the combination with a supporting-frame, a power-shaft journaled thereon, a driving-shaft also journaled upon said frame and geared to said power-shaft for driving the latter, a ratchet-wheel mounted upon said driving-shaft, reversely-arranged pawls engaging said ratchet-wheel for actuating the same, and arms for actuating said pawls, of a rocker-arm carried by said frame and having an adjustable fulcrum thereon, said rocker-arm having suitable connections for attachment to a reciprocating element to receive motion therefrom, and a guide-plate carried by said supporting-frame and having a slot in which said rocker-arm reciprocates, whereby said rocker-arm is prevented moving laterally upon its fulcrum, said guide-plate being vertically adjustable upon said frame, whereby said plate may be raised or lowered to accord with the change of pitch of the rocker-arm when the fulcrum-point of the latter is changed. 75

CHARLES S. AITKEN.

In presence of—

W. C. HARRIS,
M. H. PAYNTER.
